UNITED STATES PATENT OFFICE.

FRANK A. REECE, OF HOPKINTON, MASSACHUSETTS.

AUTOMOBILE-HEADLIGHT.

1,331,211.

Specification of Letters Patent. Patented Feb. 17, 1920.

Application filed August 8, 1917. Serial No. 185,153.

To all whom it may concern:

- Be it known that I, FRANK A. REECE, a citizen of the United States, residing at Hopkinton, county of Middlesex, State of Massachusetts, have invented a certain new and useful Improvement in Automobile-Headlights, of which the following is a specification, reference being had therein to the accompanying drawings.
- 10 My invention has for its object a device conveniently called a dimming screen to be placed in front of an ordinary head light, such as is used on automobiles and which has a parabolic or substantially parabolic reflector, and is for the purpose of preventing glare above a predetermined point at a distance from the headlight. The device consists essentially of a series of horizontal or substantially horizontal slats or plates 15 together forming a screen through which rays which are traveling in a horizontal plane can pass freely while rays which are traveling upward and therefore would tend to be blinding are intercepted. The 20 several slats of which the device is composed are relatively wide and are placed close together and accurately spaced and alined, so that only such rays as are practically horizontal can pass between them. They must 25 be held in place so securely that the vibration to which the car is subjected will not cause them to change their position or to rattle. As the slats are made very thin so that the percentage of the horizontal rays 30 intercepted by the edges of the slats will be reduced to a minimum, considerable difficulty has been experienced in securing them satisfactorily in place throughout their entire length. The dimming screen embodying 35 my invention is so constructed that it can be made at a minimum of expense. The slats composing it are perfectly alined and the whole is secured together in such a manner that no part of it can rattle or get out of 40 alinement. With a single exception, no solder or brazing is employed, and therefore the work of manufacture is reduced to a minimum.
- The invention will be fully understood 45 from the following description taken in connection with the accompanying drawings, and the novel features thereof are pointed out and clearly defined in the claims at the close of this specification.
- 50 In the drawings Figure 1 is a front eleva-
- tion of a lamp provided with a dimming screen embodying my invention.
- Fig. 2 is a section on line 2—2 Fig. 1.
- Figs. 3 and 4 are detail views of the slats.
- Fig. 5 is a detail showing a modified form 60 of slat.
- Referring to the drawings, at 11 is shown an outer casing surrounding the main headlight A and the auxiliary light B. The dimming screen is placed in front of the 65 upper half of the main head light only, and is held in place between the glass 14 and an inner ring, as will be described. The outer casing 11 is provided with a circular flange 12, the front edge of which is inturned as 70 shown at 13, to provide an edge against which the glass 14 rests. The ring 12 protrudes beyond the front of the lamp a distance equal to the width of the slats 15 composing the screen. The slats extend 75 across the lamp from one side to the other with their front edge horizontal. Their top surfaces are at right angles to the plane of the glass 14 and are therefore horizontal if the glass 14 is placed in a vertical position. In actual practice, however, it is customary to incline the entire lamp downwardly so that a ray of light passing between the adjacent slats will strike the ground at least 200 feet from the car if the 80 lamp is supported about $3\frac{1}{2}$ feet above the ground. The slats are made of very thin sheet metal, either bright or dull. In practice, I make them about one one-hundredth of an inch in thickness and make the space 85 between each pair of slats about one-eighth of an inch. The slats are preferably of a width which is about one-eighth the diameter of the lamp. These proportions may be varied somewhat according to the size of the 90 lamp, but substantially these proportions are essential to produce a satisfactory result.
- The lowest slat 15 is permanently secured at its ends to a section of the ring 12 and is also supported in the center by a vertical strut 16, secured at its lower end to the ring section 12. Next above the slat 15 is a slat 15^a which has five U-shaped loops e see Fig. 3, formed at intervals 10 throughout its length by bending the slat upon itself. Two of these U-shaped loops are at the extreme end of the slat. The slat is of such a length that it will fill the entire space between the sides of the lamp except 11

for the space occupied by a felt strip 17 interposed between the ends of the slats and the ring 12. The other loops *e* are spaced so that the slat will be supported by the loops 5 which contact with the lower slat 15 at substantially equi-distant points. The slat 15^a which is just above the slat 15^a is substantially the same in construction except that the intermediate loops are spaced some- 10 what differently. The loops on the other slats are arranged similarly so that when all the slats are assembled there will be six vertical rows of loops and further so that the loop of one slat will not rest on the loop 15 of the slat below. The loops on the sides of the upper slats are spaced somewhat differently as will be seen from the drawing, to allow for the curvature of the upper 15 part of the ring. The construction of 20 the loops at the ends of the slats varies somewhat. The loops at the ends of the lower slats are made as shown in Fig. 3. The loops at the ends of the slats above these are made as shown in Fig. 4. The 25 loops at the ends of the slats above these are made as shown in Fig. 3; the slats at the top of the lamp are also constructed as shown in Fig. 3. This construction is such that the ends of the slats receive a satisfactory support from the felt strip 17 and ring 12. At 18, is shown a felt ring which rests against the ends of the edges of the slats on their rear side. At 19, is shown the inner or clamping ring which compresses 30 the felt washer 18 against the rear end of the slats and forces the front ends of the slats against the felt washer 141, pressure 35

being provided by means of screws 20, 20. This construction is such that the whole device is locked securely in place. While it is 40 not absolutely necessary to do so, it is desirable to braze or solder in the ends of the lower slat 15 and the strut 16 to the ring section 12.

While I consider the U-shaped loop of 45 the form shown in Figs. 1, 3 and 4 the most satisfactory, I do not limit myself to this form, as under certain conditions other forms may be employed successfully without departing from the spirit of the invention, for instance, the form shown in Fig. 5 which is substantially semi-circular in shape. This is somewhat easier to manufacture than the U-shaped form previously described. 50

55 What I claim is:—

1. A dimming screen for a headlight comprising a ring, a glass, and a series of slats within the said ring spaced apart from each other by loops formed by bending the slats, 60 and a ring within the first mentioned ring, adapted to compress the slats between the two said rings.

2. A dimming screen for headlights which comprises a series of slats occupying the upper portion of the head light, the lower member of the lower slat being supported by a vertical strut and the slats above said lower slat being spaced apart from each other and supported by loops formed by 65 bending the slats upon themselves. 70

In testimony whereof I affix my signature.

FRANK A. REECE.
